[57] CLAIM

The ornamental design for a plumbing fitting handle or the like, as shown and described.

DESCRIPTION

FIG. 1 is a perspective view taken from the top, front and left side of a plumbing fitting handle or the like showing my new design;

FIG. 2 is a front elevational view thereof;

FIG. 3 is a left side elevational view thereof, the right side being a mirror image of the left side;

FIG. 4 is a rear elevational view thereof;

FIG. 5 is a top plan view thereof;

FIG. 6 is a bottom plan view thereof;

FIG. 7 is a cross-sectional view taken on line 7—7 of FIG. 5; and,

FIG. 8 is a left side elevational view of a second embodiment thereof, wherein the change resides in the omission of the upswept bottom contour.
